UNITED STATES PATENT OFFICE.

RUDOLPH FURRER, OF MILWAUKEE, WISCONSIN, ASSIGNOR TO A. O. SMITH CORPORATION, OF MILWAUKEE, WISCONSIN, A CORPORATION OF NEW YORK.

TIME-INDICATING DEVICE FOR METAL-WORKING PRESSES.

Application filed November 9, 1923. Serial No. 673,830.

To all whom it may concern:

Be it known that I, RUDOLPH FURRER, a citizen of the United States, and a resident of the city of Milwaukee, county of Milwaukee and State of Wisconsin, have invented certain new and useful Improvements in Time-Indicating Devices for Metal-Working Presses; and I do declare the following to be a clear, exact, and complete description thereof, such as will enable others skilled in the art to which the invention pertains to make and use the same, reference being had to the accompanying drawing for an illustration of a construction in which my invention has been embodied.

The present invention relates to the operating or driving means for the assembly of presses in the side bar forming line disclosed in Patent No. 1,477,778, granted December 18, 1923, to R. Stanley Smith, in which sets, comprising curved right and left hand side bars for automobile or other vehicle frames, are produced in a regular sequence of pairs. But the invention is not to be restricted to the use specified in the said patent.

The said patent discloses, among other things, an assembly of co-operating presses which perform certain preparatory or intermediate as well as the finishing operations in the process of converting sheet metal strips into curved, flanged side bars in their completed state. Such preparatory or intermediate operations comprise the steps of bending the metal strips in the direction of their width so as to increase the available area thereof and permit the cutting of curved blanks which ordinarily would require for their production strips of much greater width, removing the marginal portions of such strips so as to produce curved blanks of the desired contour, and perforating the said blanks for the accommodation of the rivets employed to unite the elements of the frame in which such elements are embodied in the formation of a permanent structure. The finishing operations consist in turning the side margins of the curved blanks so as to produce curved channels having spaced reinforcing flanges extended from the web at one side thereof.

The several presses of the line are operated by a common driving means in suc-

cession through a timed cycle, a fraction or division of the cycle being allotted to each press for the performance of its particular function, so that a peak load is never thrown upon the driving means at any instant of time in its operation. As is also disclosed in the said patent, the several separate presses in the line are clutched to the main driving shaft for operation as a unit, but each press may be disconnected from the line shaft and operated independently thereof, when adjustment of any of its parts, or a try-out prior to line operation, becomes necessary. For the purpose of accomplishing this independent operation, each press is equipped with a separate driving motor which is adapted to be coupled to the press to operate the latter when disconnected from the main driving shaft.

After the separate presses have been tried out and found ready for connection to the line driving shaft, it is necessary that they first be lined up, so that when coupled to the line shaft, they will all operate in the allotted divisions of the time cycle.

The purpose of the present invention is to provide means for lining up or time indicating the presses, so that the cycles of their operation as a unit and their allotment to the fractions of the time cycle may be definitely ascertained and determined by bringing them into a position of register before coupling to the line shaft.

The invention comprises a plurality of presses adapted for successive operation as a unit through an apportioned time cycle, and means for so operating them, together with means for operating them independently.

Viewed in another aspect, the invention also comprises devices which will indicate the timing of the several presses, so that by visual inspection it may be determined whether the presses of the line are operating in the desired order.

The invention further comprises other features which will hereinafter be described more specifically. The novelty of the whole will be pointed out in the appended claims.

In the drawing herewith:

Figure 1 is a diagrammatic plan view of a line of presses adapted to the production of curved flanged bars from metal strips,

together with the line driving and independent driving means therefor.

Fig. 2 is a vertical sectional view showing the means for driving one of the presses 5 from the line as well as for driving the same independently, together with the connections which operate the time indicating mechanism.

Fig. 3 is a face view of the visual indicator of the timing mechanism.

In the drawing, the offsetting press is indicated by the letter A, the successively acting blanking presses by the letters B and C, the piercing press by the letter D, and 15 the forming presses for drawing the side bar flanges into shape by the letters E and F.

A main motor 20, of sufficient power to carry the largest of the loads which may 20 occur in the operation of the assemblage, drives a line or main shaft 21, and the latter through branch shafts 22, drives the several presses coupled in the group as a unit. The line shaft 21 has fixed thereon bevel gears 25 23, equal in number to the number of presses employed in the assemblage. The said bevel gears 23 are in mesh with bevel gears 24 fixed upon the near ends of the said branch shafts 22. At the other end, each shaft 22 30 is provided with a pinion 39, in engagement with a gear 40 upon the operating shaft for driving the press. Each branch shaft 22 is formed of two aligned parts 25 and 26, one end of the part 25 being reduced as at 35 27, and fitted loosely in a concentric bore 28, in the contiguous end 31 of the part 26. The two part shaft 22 is supported in a housing 29. Upon and near the other end of the part 25 of the shaft 22, and within 40 the housing 29, is fastened a clutch hub 30. Splined on the end 31 of the part 26 of the shaft 22, is a sliding clutch member 32, both ends of the said sliding clutch member being provided with clutch faces, one of which 45 is designed to engage the clutch face of the hub 30, fixed upon the part 25 of the shaft 22. With the clutch faces thus engaged, the movement of the line shaft 21 is transmitted to the presses as a group or unit through 50 the coupled parts 25 and 26 of the shaft 22.

Rotating loosely upon the part 26 of the shaft 22, and within the housing 29, is a gear wheel 33, provided upon one face thereof with a clutch hub 34, the latter being 55 adapted to be engaged by the clutch face upon the other end of the sliding clutch member 32, when the said sliding clutch member is thrown out of engagement with the clutch hub 30.

60 Each press in the assemblage is provided with a small normally inoperative independent motor 35, upon the end of the shaft of which is a pinion 36. These small motors will be of such horse power as will enable 65 them to separately operate the presses to

which they may be connected. Journalled 70 in the housing 29, is a shaft 360, driven by a fixed gear 37, in engagement with the pinion 36, upon the end of the shaft of the motor 35. The said shaft 360, has also fixed thereon, a pinion 38, the latter being in 75 mesh with the gear 33, rotating loosely upon the part 26 of the branch shaft 22. With the engagement of the clutch parts 32 and 34, the loose gear 33 becomes relatively fixed upon the part 26 of the shaft 22, and transmits motion to the connected press, which may thus be independently operated.

The double faced splined clutch member 32 may be moved along the shaft 22, to disengage the said clutch member from the clutch hub 30, and while I have shown a hand lever 41 for operating the clutch mechanism separately, it will be obvious that the clutch operating levers may be simultaneously actuated by a device which will throw 90 all of the clutches into or out of engagement in a single movement. When all of the presses are coupled through their clutches, they will be operated as a unit by means of the line driving shaft 21, and 95 when the clutches are thrown out, each press may be operated independently by the small motor 35, provided therefor. The splined clutch member 32 cannot be in engagement with both of the clutch hubs 30 and 34 at 100 the same time, but may occupy a position of engagement with either clutch hub 30 or 34. When the sliding clutch member 32 is thrown into engagement with the clutch hub 34 of the loosely rotating gear wheel 105 33, the auxiliary motor 35, may, through the connections described, impart movement to the particular press which is arranged to be driven by the said auxiliary motor 35. This motion will take place while the motor 20 and the line shaft 21 are at rest, and the small motors 35 may thus be independently driven for a trial of the press, with an opportunity to perfect such adjustments as may be necessary, before operating the assemblage as a whole. After the presses have been tested and adjusted, the independently operating connections will be disconnected and the shafts 22 will be 110 clutched for operation by the line shaft 21. The presses in the group may now be operated as a unit by the large motor 20.

After the presses have been separately tested and adjusted, it is necessary that they be set so that when coupled to the main or line driving shaft 21, the presses will operate in exact and predetermined time, each press performing its operation in that fraction of the time cycle allotted for such operation. To enable the working position of the several presses in their relation to each other to be ascertained, I provide each press with a visual indicator, which will indicate the position of the mechanism of the press 115 120 125 130

at any moment. The shaft sections 25 and 26 are provided with sprockets 42 and 43 respectively, which through chains 44 and 440 drive sprockets 46 and 47, mounted upon 5 the shafts 48 and 49, journaled in a stand 60, which is mounted upon the gear casing 29. A ring 61 attached to a tubular shaft journaled in the said stand 60, is driven from the shaft 48 through the medium of 10 worm gears and bevel gears as shown. Motion is transmitted from the worm gear to the bevel gears through the tubular shaft also mounted in the stand 60. A disk 62 is mounted upon the end of a shaft which 15 is journaled in the tubular shaft of the ring 61. This disk is driven from the shaft 49 by means of a small worm gear and bevel gear connection, the shaft connecting the last mentioned worm gear and bevel gears 20 rotating in its companion tubular shaft as shown in Fig. 2. The ring 61 and the disk 62 are designed to be operated with their indicators in exact registry, the disk 62 being provided with a marker 63 which points 25 toward a marker 64 upon the said ring. The disks 62 and rings 61 are rotated in unison by means of the connections from the two parts of the shaft 22, when coupled together by the clutch 32, but when the 30 clutch is thrown out so as to disconnect the presses from the line shaft 21, the ring 61 will remain at rest by reason of the inactivity of the part 25 of the shaft 22. The disk 62 will always rotate in the movement of 35 the press with which it is associated, inasmuch as the part 26 of the shaft 22 is rotated constantly, whether by the main motor 20 or by the independent motor 35. When the indicators upon the disk and ring 40 are properly set, mere inspection of the device will indicate whether the press is operating in the desired timing. The disk 62 may be provided with additional markers 65, which will indicate the extent of 45 the displacement or lack of registry, if there be any, in the operation of the press. By proper location of the additional markers 65, with reference to the speed of rotation of the parts the distance which the press 50 will have to be turned to bring the parts again in correct registry, may be easily ascertained. The position of the presses thus being indicated, it will be an easy matter to turn over such of the presses as may 55 be necessary to bring them into the relative positions which they are to occupy while operating as a unit. This adjustment having been effected, the presses will then be operated from the line shaft 21, and in 60 the order desired, after the clutch members 32 have been shifted into engagement with the clutch faces 30, and the main motor 20 thrown into circuit.

The numeral 45 indicates the step-by-step 65 conveyor mechanism, which may be as dis-

closed in the patent to R. S. Smith first hereinbefore referred to.

Having thus described my invention, what I claim and desire to secure by Letters Patent of the United States, is:

1. In an apparatus of the character specified, a line of presses adapted to perform progressively a series of preparatory operations upon parts-forming elements to effect completion of the latter, conveying devices for the elements, and a line driving shaft for operating all of the presses in succession through an apportioned time cycle, in combination with means for disconnecting the presses from their operating line shaft, and devices associated with the presses for indicating the relative timing of the latter during their operation.

2. In an apparatus of the character specified, a line of presses adapted to perform progressively a series of preparatory operations upon parts-forming elements to effect completion of the latter, conveying devices for the elements, and a line driving shaft for operating all of the presses in succession through an apportioned time cycle, in combination with means for disconnecting the presses from their operating line shaft, and devices associated with the presses for indicating visually the relative timing of the latter during their operation.

3. A line of presses adjusted for successive and consecutive operation in an apportioned time cycle, means for operating such presses to perform progressive preparatory operations upon parts-forming elements to effect completion of the latter in the time cycle, and a conveyor for feeding the elements from press to press, in combination with devices for disconnecting the presses from their operating means, means for separately operating the presses, and devices associated with the presses for indicating the relative timing of the latter during their operation.

4. In an apparatus of the character specified, a line of presses adapted to perform a series of preparatory operations upon parts-forming elements to effect completion of the latter, devices for conveying the elements from press to press, and a line driving shaft for joint operating all of the presses, in combination with devices for disconnecting the presses from the line shaft, means for operating the presses independently of each other for testing purposes, and means associated with each of the presses for indicating their relative timing when operated as a unit from the line shaft.

5. In an apparatus of the character specified, a line of presses adapted to perform a series of preparatory operations upon parts-forming elements to effect completion of the latter, devices for conveying the elements from press to press, a line driving shaft for jointly operating all of the presses, and

means associated with the several presses to indicate their relative timing when operated as a unit from the line shaft, in combination with clutch mechanisms through which the 5 presses may be disconnected from the line shaft to permit their independent operation.

6. In an apparatus of the character specified, a line of presses adapted to perform a series of preparatory operations upon parts-
10 forming elements to effect completion of the latter, devices for conveying the elements from press to press, a line driving shaft for jointly operating all of the presses, and means associated with the several presses to
15 indicate their relative timing when operated as a unit from the line shaft, in combination with clutch mechanisms through which the presses may be disconnected from the line shaft to permit their independent operation,
20 such disconnecting clutch mechanism comprising a two part branch shaft and connections therefrom to the indicating means to actuate the latter.

7. In an apparatus of the character described, a line of presses adapted to perform a succession of preparatory operations upon parts-forming elements to effect completion of the latter, devices for conveying the elements from press to press, a line driving shaft for jointly operating all of the presses, means including rotating indicators associated with each of the presses for indicating the time of their operation with relation to each other, in combination with
30 branch shafts connecting the line driving shafts with the several presses, connections from the branch shafts to effect rotation of the indicators, and means for disconnecting the presses from the line shaft to permit
35 their independent operation.

8. In an apparatus of the character described, a plurality of presses and a line shaft for operating them jointly, an indicating device composed of two rotating parts associated with each press for indicating the time of the operation of the presses

with relation to each other, connections actuated from the line shaft for rotating the parts of the indicator in unison, and means for conveying the parts-forming elements from press to press, in combination with devices for effecting disconnection of the several presses from the line shaft to permit their independent operation for testing purposes.

9. In an apparatus of the character described, a press and a driving shaft for actuating the same, an indicator connected with and actuated from the shaft for indicating the time of operation of the press with relation to the rotation of the shaft, in combination with means for disconnecting the press from the line shaft to permit independent operation of the press, and means actuated in such independent operation for indicating that the press is properly timed for connection to its driving shaft.

10. In an apparatus of the character specified, a line of presses adjusted for consecutive and successive operation in an apportioned time cycle, a line shaft for driving the presses as a unit, and branch shafts connecting the line shaft with the presses, such branch shafts each being composed of
70 two sections, and a clutch for effecting their rotation as one part, in combination with devices for indicating the relative timing of the presses with relation to their driving shaft, such indicating devices comprising
75 two rotating parts and connections from both sections of the branch shaft thereto, whereby the indicator parts of each press are rotated in unison, and means for disconnecting the presses from the line driving shaft to permit their independent operation
80 for testing purposes.

In testimony whereof, I have signed my name at Milwaukee, this 6th day of November, 1923.

RUDOLPH FURRER.
